UNITED STATES PATENT OFFICE

2,440,553

AMPLIFIER SYSTEM

Montford Morrison, Upper Montclair, N. J.

Application August 5, 1943, Serial No. 497,497

3 Claims. (Cl. 179—171)

1

This invention relates to amplifier and detector systems with regenerative feed-back, and relates in particular to the stabilization of such systems.

Among the objects of the invention are; to provide a system of regenerative amplification and detection for certain types of signal-currents which system does not produce heterodyne effect in the output circuit; to provide a receiving circuit filter-system for certain types of signal-currents which effects a sharpness of tuning corresponding to a higher Q than present in the structural design of the filter per se; to provide an amplifier-detector system for certain types of signal-currents which produces a relatively high output level and which level is, within wide limits, not sensitive to the voltage level of the input signal; and to provide positive stabilization in a regenerative, non-heterodyning amplifier-detector circuit for certain types of signal currents.

These and other objects will be obvious upon reading the specification in connection with the accompanying drawings, in which Fig. 1 shows an embodiment of the invention in a voice-frequency carrier telegraph receiving circuit; and Fig. 2 shows a series of oscillograms illustrating some of the characteristics of the circuits shown in Fig. 1, operating under the present invention.

In order to properly define the scope of this invention, it will be advantageous to review and define the pertinent prior art.

In this specification, degenerative amplifiers are considered as not coming within the category of regenerative amplifiers.

This invention has particular application to embodiment in tuned circuit amplifiers in which the output current does not necessarily bear a close qualitative relation to that of the input signal. Since in the literature relating to the pertinent prior art, there has been considerable confusion in the nomenclature as well as in the operative theory, I shall not only distinguish and define the two pertinent groups, but also shall review the precise operative theory, in order that the present invention may be clearly distinguished from them.

These two pertinent groups of devices are correctly referred to as oscillating and regenerative detectors, although the literature quite often confuses the two. It may be well to recall at this point that these devices are, in fact, amplifiers as well as detectors.

In the case of the oscillating detector, the feed-back is sufficient to set up continuous oscillations in the output circuit to which the signal trans-

2

lator does not respond because of the oscillating frequency being above the response frequency of the translator. If a signal frequency is injected into the input circuit and which signal frequency is sufficiently different from the oscillator frequency, and at the same time within the band of frequency transmission of the tuned circuit, this input signal frequency may be superimposed upon the oscillator frequency, heterodyning with it and producing a resultant frequency to which the output translator will respond. As the injected signal input frequency approaches very closely to that of the oscillator frequency, the oscillator is forced to oscillate at the signal frequency, producing the so-called silent region. In other words, this amplifier-detector becomes inoperative for the purpose for which it is intended at the point where heterodyning ceases.

In this class of amplifier-detectors, the feed-back energy is limited by the use of a grid-leak condenser structure, that is, by a self-adjusting bias applied to the grid circuit, and in some cases, by the saturation characteristic of the plate current of the tube employed. With an increase in signal current, either per se, or with amplification and by regeneration (if the tube is working below plate-saturation), the plate current is increased also by an appreciably larger amount. These operative characteristics are pointed out as they will be hereinafter referred to.

The regenerative detector, while resembling the oscillating detector in circuit, and in fact only structurally differing from it in the matter of feed-back adjustment, operates on a widely different principle.

The feed-back is adjusted to a point where oscillations in the local circuit do not occur, or at least are reduced to a very low amplitude. The local circuit, which is subject to oscillation under operation, is tuned to a frequency which will heterodyne with that of the incoming signal. When the incoming signal is injected into the input circuit and amplified with the additional effect of regeneration due to the feed-back circuit, this amplified signal energy in the plate circuit becomes a source of energy for the local tuned circuit, providing the power required for its oscillation and heterodyning, as in the case of the oscillating detector. The regenerative detector thus operates like two differently-tuned circuits in parallel, which are coupled together and which has energy fed to one directly, the other acquiring its energy by coupling effect. The regenerative detector, like the oscillating detector, does not respond operatively in its output circuit, except

when heterodyning, and the stability required, if and when possible, is due, in addition to the critical adjustment of the feed-back circuit, to the condenser grid-leak and/or to the saturation characteristics of the plate current.

The present invention is distinguished from the pertinent circuits of the prior art by several important structural and operative characteristics, among which are; there is no heterodyning in the output circuit; the tube or tubes never work under conditions of plate current saturation; the grid-cathode impedance of the tube used in the output circuit is never relatively any appreciable value of that of the total grid circuit; the feed-back circuit always contains a very high impedance; the positive voltage level of the output tube grid never rises substantially above the zero value; and many other differences will be pointed out and obvious in the description hereinafter given.

In Fig. 1, 1 is the output transformer of a receiving amplifier of a voice frequency carrier telegraph system; 2 is a channel comprising a single stage inductively coupled filter 3 feeding into a class A₁ amplifier 4, which is resistance-capacitance coupled to a detector tube 5 having an electro-magnetic relay 6 inserted as a load in the plate circuit, with the plate circuit shunted by a condenser 7. The resistors 8 and 9 have a very high value in comparison to the grid-cathode impedance of tube 5; the plate circuit of tube 5 supplies feed-back current to filter 3 through a high resistance 10 having a conventional blocking condenser 11 inserted.

12 is a second channel identical with channel 2, with the exception of having an additional stage inserted into the filter circuit 13, by employment of the reactor 14 and the condenser 15. In this particular channel, the feed-back from the output tube through the resistor 16 is made between the reactor 14 and the condenser of the filter 13.

The connection of the feed-back circuit into the filter system depends upon the phase position of the harmonic in the feed-back current that is used for feed-back purposes, with relation to the phase position of the corresponding frequency in the filter system and which phase position in the filter system is affected by filter design as well as reflections within the filter itself.

Since the filter used in the embodiment of this invention shown in Fig. 1 operates into a class A₁ amplifier, the ohmic resistance of the circuit comprising the end section 17 of filter 3, channel 2, as well as the corresponding circuit in channel 12, may be included in the reactor of that circuit and thereby decreasing the physical size of this reactor over what would be required by the use of an external resistor.

The feed-back energy received by this filter circuit serves to neutralize a large portion of the filter insertion losses, thereby greatly increasing the Q of the filter reactors, and thus not only decreasing the over-all size of the filter circuit, but also greatly increasing the sharpness of tuning.

Further, the resistors 10 and 16 have such a high value in comparison with the impedance of the filters in series with these resistors, that the impedance of the filters themselves contribute no appreciable effect to the impedance of the feed-back circuit as a whole. Therefore, the current in this feed-back circuit is rather strictly directly proportional to the plate current of the output tube, and the voltage developed in

the filter by the feed-back current is determined by the selectivity of the filter itself. In other words, irrespective of the shape of the wave form of the plate voltage of the output tube and the identical shape of the feed-back current, the filter voltage only takes from that wave form the harmonic component in a very pure form, corresponding to the carrier frequency of the particular channel involved. Therefore, the particular channel under consideration picks out of the feed-back current the correct harmonic component (when its phase position is correct) and utilizes this component in the regenerative amplification employed in the system.

15 The impedance of filter 3 to feed-back current of the proper carrier frequency at the point of injection of the feed-back current in the said filter, has a very low value looking east and a very high value looking west. In actual practice, under operating conditions, the presence of feed-back current from resistor 10 in output transformer 1 is not detectable in comparison with the amplitude of the corresponding harmonic in output transformer 1 that is received as signal current.

20 Referring to Fig. 2, abscissa A illustrates in a general way the amplitude of the voltage across the coil 18 in Fig. 1, due to signal current alone. Abscissa B shows a relative amplitude of the voltage across the same coil under feed-back operation. Abscissa C shows the wave form of the voltage applied to the grid of amplifier tube 19. Abscissa D shows typical voltage wave forms developed across resistor 9 included in the grid circuit of the output tube 5.

25 The grid bias battery 20 of Fig. 1 has a voltage value indicated by the height 20 from the abscissa D in Fig. 2. The resistor 9 of Fig. 1 may have a value as high as the order of one megohm, and the current produced in such a resistor may be of the order of a few micro-amperes. The ability of the class A₁ amplifier to reproduce the wave form shown at C in the resistor 9 depends upon the value of the resistor being constant and of a very high value, which operating conditions obtain so long as the grid of tube 5 does not draw any current. However, as soon as the instantaneous amplitude of the positive lobe of the alternating voltage produced in 9 exceeds the bias voltage 20, the grid, of course, begins to draw current and the 30 impedance between the grid and the cathode of tube 5 drops to a relatively low value. Because of the relatively small amount of current available in resistor 9 and relatively considerable amount of carrying capacity available between the grid and cathode of tube 5, practically all of the energy available in resistor 9 represented at voltage value in excess of the bias 20 is shunted through the grid cathode circuit tube 5, as will be fully understood by those familiar with the art 35 to which this invention appertains.

40 Referring to Fig. 2, abscissa D, curve 21 represents the wave form of voltage applied to the grid of tube 5 when the maximum amplitude of the said voltage is less than the grid bias, producing 45 in the plate circuit a current corresponding to 22, abscissa E, and a plate voltage of the form represented by 23, abscissa F. If and when the voltage across resistor 9 rises above this value, it 50 may assume the wave-form 24, abscissa D, which has a sharply truncated positive lobe 25 producing a truncated lobe 26, abscissa E, in the plate 55 current and a corresponding plate voltage 27, abscissa F.

Again, if the voltage across resistor 9 is further 60 raised, the wave form corresponding to 28 hav-

ing a wider truncated positive lobe 29 produces a wider truncated lobe of plate current 30, abscissa E, and a corresponding plate voltage 31, abscissa F.

While the truncations of the lobes of the waveforms illustrated along abscissa D are represented as being parallel to that abscissa, they do, in fact, rise some slight amount depending upon the circuit parameters involved, but for all practical purposes in a well-designed circuit, these may be considered as substantially flat. It will be observed that the plate voltages of the output tube, as illustrated along abscissa F, decrease in magnitude of variation with an increase in grid voltage, thereby producing a positive stabilization in the amplifier circuit.

This highly important stabilizing effect results in a circuit which is highly stable to large variations in operating conditions, and, entirely unlike other regenerative feed-back amplifiers, does not tend to oscillate or operate out of control.

While I have used two triodes in teaching the use of my invention in the embodiment described in this specification, I do not limit myself to the number of tubes nor to the type of tube used, as my invention may be embodied in circuits having one triode or one multi-grid tube, as will be fully understood by those skilled in the art to which this invention appertains, upon having learned the teachings of this specification.

It is pointed out that in the claims hereunder, the terms internal and external do not refer to the tubes employed but only to indicate that separate circuits are employed, and of course are coupled in the same sense that in a conventional regenerative or oscillating detector employing a pentode tube, the feed-back is external of the input and output circuits. The expressions input and output circuits are used to mean these circuits per se or, of course, circuits coupled with them.

What I claim is:

1. The method of signal-current amplification by regeneration which comprises receiving signal current, filtering out of said current a form of wave comprised of a narrow band of sinusoidal frequencies, amplifying said wave and truncating said form producing a flat-top pulsating current,

discharging said current through means reducing the amplitude of the pulsation of said current and feeding back from last said current into first said current for regeneration, a current proportional to the amplitude of the reduced pulsations in said means.

2. The method of signal-current amplification by regeneration which comprises receiving signal current, filtering out of said current a form of wave comprised of a narrow band of sinusoidal frequencies, amplifying said wave and truncating said form producing a flat-top pulsating current, discharging said current through means reducing the amplitude of the pulsation of said current, conducting feed-back energy from last said current into first said current for regeneration and employing the reducing-of-the-amplitude characteristic to stabilize the amplifying of said wave.

3. The method of signal-current amplification by regeneration which comprises receiving signal current, amplifying said current and converting the form thereof into a wave having a direct current component, discharging said wave into means having a direct-current storage characteristic, conducting feed-back current from said means into first said current for regeneration and employing said direct-current storage characteristic to limit said feed-back current to a stable amount.
